United States Patent Office

Des. 215,578
Patented Oct. 14, 1969

215,578

BUILDING

Charles L. Brown, Rte. 1, Box 149,
Coppell, Tex. 75019

Filed Sept. 11, 1968, Ser. No. 13,499

Term of patent 14 years

Int. Cl. D25—04

U.S. Cl. D13—1

Fig. 1

Fig. 2

Fig. 3

Fig. 4

FIGURE 1 is a top plan view of a building, showing my new design;

FIGURE 2 is a front elevational view thereof;

FIGURE 3 is a side elevational view thereof; and

FIGURE 4 is a rear elevational view thereof.

The side of the building opposite that illustrated in FIGURE 3 includes a single door.

I claim:

The ornamental design for a building, as shown and described.
